UNITED STATES PATENT OFFICE.

JOHN GALLIMORE AND DANIEL COOK, OF EDINBURGH, SCOTLAND.

GAS OVEN OR FURNACE.

1,323,041.

Specification of Letters Patent. Patented Nov. 25, 1919.

Application filed January 10, 1917. Serial No. 141,656.

To all whom it may concern:

Be it known that we, JOHN GALLIMORE and DANIEL COOK, subjects of the King of Great Britain, and residents of Edinburgh, 5 Scotland, have invented certain new and useful Improvements in Gas Ovens or Furnaces, of which the following is a specification.

This invention relates to improvements 10 connected with gas ovens or furnaces and has reference particularly to gas ovens having a multiplicity of burners.

The primary object of the invention is to provide means whereby all the burners may 15 be controlled from a central point in such a manner as to maintain a constant pressure on the gas supplied to each burner.

A further object of the invention is to provide means whereby the conditions under 20 which the burners are being employed at any given time can be readily ascertained, and a further object is to provide convenient and economical means by which the burners can be lighted. The invention 25 therefore consists broadly in the provision of means whereby the number of burners in use can be readily controlled within certain limits from a central position in contradistinction to the reduction of the supply and 30 pressure to all the burners.

A further feature of the invention is the provision of an igniting burner adapted to light all of a series and itself be ignited by a single pilot light.

35 A further feature consists in providing an interlocking means whereby the turning on of the burners cannot occur until after the igniting burner has been lighted and means whereby when the burners have been lighted 40 the igniting burner can be turned out, and a further feature consists of an indicator associated with the control valve by means of which the number of burners in use can be readily ascertained at any time.

45 In the accompanying drawings we have illustrated a practical embodiment of the invention, Figure 1 being a longitudinal elevation of a gas oven with our invention applied thereto.

50 Fig. 2 is a sectional plan of Fig. 1.

Fig. 3 is a cross section on line A—A of Fig. 1.

Fig. 4 is a part sectional elevation of the control valve chamber.

55 Fig. 5 is a part sectional plan view of Fig. 4.

Fig. 6 is a section on line B—B of Fig. 4 looking in the direction of the arrow.

Fig. 7 is an end view of a part of Fig. 4.

Referring to these drawings the numerals 60 1, 1^a, 1^b, 1^c designate multiple valves grouped together at some convenient point where the gas supply is connected for instance by means of a pipe 2. These valves are provided with ports 3 to supply variable groups 65 of burners 4, 4^a, 4^b, 4^c, and the turning of index plates 5 operates to alter the number of burners turned on or off.

If we take as an example a traveling chain oven say 45 feet long with 28 burners on 70 the top and 28 burners on the bottom, these may be divided into four main groups with a multiple valve to each main group.

If we regard the oven as divided in two lengthwise and call one end F the feed end 75 and the other end D the delivery end, we distribute the control valves as follows: one designated 1 to the top feed end burners; one designated 1^a to the bottom feed end burners; one designated 1^b to the top delivery end burners, and the remaining one designated 1^c to the bottom delivery end 80 burners.

Each of these groups can be subdivided into any number of smaller groups. As an 85 example we will assume each valve to supply three different groups of burners containing 3, 5 and 6 burner in each group respectively. In this example the indicator 5 on the valve would show eight different 90 valves, viz. 3, 5, 6, 8, 9, 11, 14 and off, showing eight different positions for the valve as indicated at E Fig. 5. It will be seen upon reference to Fig. 6 that from the outlet of the valve there are three supply pipes 95 to the burners; one pipe designated 6 supplies three burners, a second pipe designated 7 supplies five burners, and the third designated 8 supplies six burners.

The ports on the valve are arranged as 100 follows: one to open to the pipe 6, opening three burners, one to the pipe 7 opening five burners, and one to the pipe 8 giving six burners. The ports can be grouped to give eight burners (5 and 3), nine (6 and 3), 105 eleven (6 and 5), and fourteen (3, 5 and 6); the eighth position being blank, thus entirely cutting off all the burners. Various combinations of these four valves will give burners ranging from 3 to 56 in the whole 110 oven top and bottom.

The four valves mentioned above can be

connected to a common supply pipe or be contained in a receiving box 9 or arranged in any other convenient way.

It will be seen from the above explanation 5 that though the control of all the burners can be concentrated in a convenient position the maximum pressure of the gas is operating on all the burners in use.

The arrangement for lighting the burners 10 as they are turned on, is also controlled from a given point, preferably from the same center as the burner control valves. A convenient means for effecting this is to provide two slotted or perforated burners 10 carried 15 the full length of the oven in close proximity to the cross burner tubes in the top and bottom rows. These long burners are supplied from the main pipe or receiving box 9 as found most convenient and controlled by 20 one or more valves such as indicated at 11 Fig. 6 at the chosen center of control. When this control valve 11 is opened these long burners are lighted by means of a constant burning pilot light 12 situated at a convenient point and the flame travels the full 25 length of the oven. We have thus a lighting flame in position to light any group or all of the 28 burners respectively in the top and bottom rows. This arrangement is a considerable saving in time and labor if compared 30 with the method of lighting each burner separately, or a great saving in gas, when compared with a pilot light to each burner. When the required burners are 35 lighted this lighting flame is turned off at the valve.

We propose to provide a safety locking arrangement to prevent the gas burners proper 14 being turned on in the oven before 40 the lighting burner has been lighted. One method of effecting this is as follows: The hand wheel 15 on the burner valves are notched on the periphery as at 15^a or provided with cam surfaces to correspond with 45 the number of positions on the valve (in the example taken this is eight), and into one of these notches a lever 16 falls; this lever is connected with the lighting valve by means of suitable links 17 or by any suitable gearing, so that when the locking lever 16 is in 50 a notch the lighting valve 11 is shut and the burner valve securely locked. To make a change on the burners it will be necessary to lift the lever 16 locking the hand wheel, 55 by means of the foot pedal 16^a and the rod 16^b, and this automatically opens the lighting valve 11, and the long lighting burner is lighted in turn from the small pilot light inside the oven. The burner valve is now ad- 60 justed as desired, and a pivoted weight 18 connected to the locking lever by the connection 19 brings the lever back into the corresponding notch in the hand wheel. To give the burners in the oven time to light the 65 above mentioned weight may be cushioned

on a piston in an air cylinder or dash pot 20 which allows the weight to slowly fall.

An arrangement to show automatically at the control point the number and position of the burners actually lighted in the oven consists in providing a revolving drum or prism 21 and connecting same to the burner valves by means of suitable gearing 22, 22^a. On the periphery of this drum are fixed a number of scales or diagrams corresponding to 70 the burners in the oven. Certain burners on each scale would be specially emphasized to correspond with the groups on the valve and would indicate the number and actual position of all burners lighted at one time. Thus 75 if the valve was set to have 9 burners lighted in the oven the scale would show the nine burners and their exact position. If desired the drum or prism may be incased and the casing would be provided with an opening 80 23 admitting to view only one chart or diagram at a time. Moreover the drum may be in some circumstances replaced by a revolving disk.

What we claim and desire to secure by 90 Letters Patent is:—

1. A device of the character described comprising in combination with a plurality of burners, a plurality of groups of valves provided with ports for supplying variable 95 groups of burners, index plates for indicating the number of burners turned on or off, means for lighting the burners, a valve for controlling the lighting means, and means for preventing operation of the burner valves 100 before the lighting valve has been operated.

2. A device of the character described comprising in combination with a plurality of burners, a plurality of groups of valves provided with ports for supplying variable 105 groups of burners, index plates for indicating the number of burners turned on and off, a pilot light for lighting the burners, a lighting valve, a hand wheel on each burner valve notched on its periphery, said notches corresponding in number to the number of positions of the valve, and a lever adapted 110 to fall into the said notches connected with the lighting device.

3. A device of the character described, 115 comprising in combination with a plurality of burners, a plurality of groups of valves provided with ports for supplying variable groups of burners, index plates for indicating the number of burners turned on and out, a pilot light for lighting the burners, a lighting valve, a hand wheel connected to each burner valve and provided with notches on its periphery, said notches corresponding 120 in number to the number of positions of the valves, a lever adapted to fall into said notches, means for connecting said lever to the lighting valve, means for lifting said lever for allowing the adjustment of the burner valve, means for returning said lever 125 130

into its engagement with one of the notches in said hand wheel, means for retarding the motion of said last named means, and means for automatically indicating the number and 5 position of the burners actually in operation, substantially as described.

4. A device of the character described comprising in combination with a plurality of burners, a plurality of groups of valves 10 provided with ports for supplying variable groups of burners, index plates for indicating the number of burners turned on and off, a pilot light for lighting the burners, a lighting valve, a hand wheel connected to 15 each burner valve and provided with notches on its periphery, said notches corresponding in number to the number of positions of said valve, a lever adapted to fall into said notches, links for connecting said lever to 20 the lighting valve, a foot pedal for lifting said lever for automatically opening the lighting valve, a pivoted weight connected to said lever for returning the same into engagement with one of the notches on said 25 hand wheel, means for retarding the operation of said weight, and means for automatically indicating the number and position of the burners actually in operation, substantially as described.

30 5. A device of the character described, comprising in combination with a plurality

of burners, a plurality of groups of valves provided with ports for supplying variable groups of burners, index plates for indicating the number of burners turned on and off, a pilot light for lighting the burners, a lighting valve, a hand wheel connected to 35 each burner valve and provided with notches on its periphery, said notches corresponding in number to the number of positions of the 40 valve, a lever adapted to fall into said notches, links for connecting said lever to the lighting valve, a foot pedal for lifting said lever for automatically opening the lighting valve, a pivoted weight connected to said 45 lever for returning the same into engagement with one of the notches in said hand wheel, a dash pot, a piston operating in said dash pot and engaging said weight for retarding its operation, and a revolving 50 drum and gearing connected to said drum and said burner valves for automatically indicating the number and position of the burners actually in operation, substantially as described. 55

In testimony whereof we affix our signatures in presence of two witnesses.
